UNITED STATES PATENT OFFICE.

FLETCHER B. BURRIS, OF MINNEAPOLIS, MINNESOTA.

SNOWPLOW.

Application filed December 2, 1920. Serial No. 427,856.

To all whom it may concern:

Be it known that I, FLETCHER B. BURRIS, a citizen of the United States, residing at Minneapolis, in the county of Hennepin and 5 State of Minnesota, have invented certain new and useful Improvements in Snowplows, of which the following is a specification.

This invention relates to new and useful 10 improvements in snow plows or collectors, the primary object of the invention being to provide a device of this character which is adapted to be moved through fallen snow to plow through and to discharge from one 15 side of the device either into a conveyance or to one side of the path effected by the device plowing through the snow.

Another important object of the invention is to provide a snow plow of comparatively 20 simple and efficient construction embodying a scoop for gathering the snow and conveying means for carrying the snow from the scoop to a suitable place for discharging the same.

25 Another object of the invention is to provide a device of the above nature including an inclined conveyor casing having an opening in the under side of the upper end thereof to effect ready discharge of the snow 30 from the conveyor casing after it has reached the upper end thereof, without the use of means other than the conveyor for causing the discharge of the snow.

A still further object of the invention is 35 to provide a particularly constructed scoop comprising an open ended casing whereby snow piling upon the scoop will be prevented from passing over the top of the same so as not to be gathered and carried off by the 40 means provided for accomplishing this purpose.

Other objects and advantages of the invention will become apparent during the course of the following description.

45 In the accompanying drawings, forming a part of the application, and wherein like numerals are employed to designate like parts throughout the several views,

Figure 1 is a front elevation of the invention.

Figure 2 is a top plan thereof, with parts broken away.

Figure 3 is a transverse section taken on the line 3—3 of Figure 2, and

55 Figure 4 is a longitudinal section taken on the line 4—4 of Figure 3.

Referring to the drawings wherein for the purpose of illustration is shown the preferred embodiment of the invention, the numeral 5 designates a scoop which consists 60 of a casing of frustro pyramidal shape arranged upon its side as clearly shown in the drawings. Both ends, or more accurately speaking, the top and bottom of the casing are open, the inner end of the casing 65 being connected to a tubular conveyor casing 6 by a tubular portion 7. A side of the conveyor casing 6 adjacent its lower end is provided with an opening 8 to receive material gathered by the scoop so that the 70 material may be delivered into the tubular conveyor casing.

The inner end of the scoop casing 5 which is connected to the portion 7 is restricted, as is most clearly seen in Figure 3. The scoop 75 casing flares outwardly from the portion 7 whereby the outer end edge 9 of one side of the casing may be engaged with the ground for scooping the snow therefrom. In the present instance, the scoop casing 5 is rec- 80 tangular in cross section as clearly shown in Figure 1, but I desire to state that I do not limit myself to the number of sides which the scoop casing embodies. As the scoop casing contains two sides 10, a bottom or 85 slide 11 and a top 12, it will be apparent that snow which is scooped up by the slide 11, will be prevented from passing over the scoop by the provision of its top or roof 12. Consequently, all snow engaged by the slide 90 11 will be properly conveyed through the opening 8 into the lower end of the conveyor casing 6.

As best seen in Figures 1 and 2, the conveyor casing 6 is inclined upwardly of the 95 scoop casing and extends laterally thereof. It may also be said that the scoop casing extends laterally from and beyond the conveyor casing. The ends 13 of the casing 6 are closed as best seen in Figures 2 and 4, each 100 being provided a central aperture for the reception of opposite ends of a shaft 14 which constitutes a part of an auger having a helical rib 15 secured thereto in any suitable manner, to provide a screw conveyor. The 105 shaft of the auger extends longitudinally of the conveyor casing, through the same, both ends of the shaft being extended beyond the ends 13 of the conveyor whereby one end may be provided with a beveled gear 16 110 adapted for mesh with a similar gear 17 keyed to a power shaft which may derive its

power from any suitable source. A collar 18 is secured to the shaft within the conveyor casing to abut with the lower end thereof to prevent downward sliding movement of the shaft relative to the conveyor casing due to the latter's incline. The upper end of the shaft is threaded and extended beyond the upper end of the conveyor, and a nut or other suitable means 19 is positioned upon the extended end to abut the outer surface of the upper end of the conveyor casing 6 to co-operate with the collar 18 in preventing improper movement of the shaft.

In order that the snow or other material collected by the device may be readily discharged from the upper end of the conveyor casing by the movement of the conveyor, an opening is provided in the relative under face of the casing adjacent the upper end, and is established by cutting away the major portion of the circumference as clearly seen in Figures 2 and 3. This cutting away of the upper end of the casing permits the portion 21 of the casing to properly support the end 13 thereof, whereby the shaft 14 may be journaled therein. By referring to the Figures 1 and 3, the manner of attachment of the device to a vehicle, cart or suitable conveyance will be obvious in the light of the following explanation. The conveyor casing 6 may be supported in any suitable manner upon a conveyance just so its lower end is spaced from the ground and the casing inclined upwardly and outwardly of one side of the conveyance so that the upper end of the conveyor casing will be disposed beyond the side of the conveyance for discharging the material collected. The casing is also so arranged with respect to the conveyance that the outer larger end of the scoop casing 5 is disposed forwardly of the conveyance and in a manner whereby the outer edge 9 of the bottom or slide 11 is engaged with the ground or is arranged in slightly spaced relation thereto if found desirable.

When the invention is used the large end of the scoop casing is disposed forwardmost, and it will be obvious that snow upon the ground will be scooped up by the slide and deposited within the lower end of the conveyor casing 6. Here, the snow or other material is engaged by the helical rib 15 of the

auger and is moved upwardly toward the upper end of the conveyor casing. When the snow or other collected material reaches the opening 20 movement of the conveyor or helical rib will exert a force against the material and will cause the same to be effectively discharged through the opening to drop into a conveyance traveling alongside of the plough, or upon the ground to one side of the path being made by the device. It is intended that the conveyor may be rotated at a high speed in order that the snow collected by the scoop may be readily carried off in case of a heavy snowfall.

The foregoing description and accompanying drawings have reference to what might be considered to be the preferred or approved form of my invention. I desire it to be understood that I may make such changes in the construction, combination and arrangement of the parts, materials, dimensions, et cetera, as may prove expedient and fall within the scope of the appended claim.

Having thus described my invention, what I claim as new and desire to secure by Letters Patent is:—

A snow collector comprising a stationary tubular casing having its ends closed and adapted to be positioned in inclined relation on a vehicle with its upper end disposed beyond one side of the vehicle and its lower end in proximity to the ground, a rotatable screw or auger conveyor extending longitudinally through the casing and being journaled in the ends thereof, the relative under surface of the upper end of said tubular casing having a discharge opening, the relative side of the lower end of said tubular casing being provided with an opening, and a scoop extending laterally of the casing and having a top, bottom and sides, said scoop communicating with said opening in the lower end of the tubular casing whereby the material collected by the scoop is delivered laterally of the auger and into the path thereof through the opening in the lower end of the tubular casing.

In testimony whereof I affix my signature in presence of two witnesses,

FLETCHER B. BURRIS.
